UNITED STATES PATENT OFFICE.

GEORGE R. RICH, OF OAK PARK, ILLINOIS, ASSIGNOR TO RICH TOOL COMPANY, OF CHICAGO, ILLINOIS, A CORPORATION OF ILLINOIS.

PISTON-RING FOR INTERNAL-COMBUSTION ENGINES.

1,082,172.

Specification of Letters Patent.

Patented Dec. 23, 1913.

Application filed July 14, 1913. Serial No. 778,892.

To all whom it may concern:

Be it known that I, GEORGE R. RICH, a citizen of the United States, and a resident of Oak Park, county of Cook, and State of Illinois, have invented certain new and useful Improvements in Piston-Rings for Internal-Combustion Engines, of which the following is declared to be a full, clear, and exact description.

10 This invention relates to piston rings, designed particularly for use in connection with pistons of internal combustion engines, and its principal object is to provide a piston ring of simple, light and comparatively inexpensive construction, yet one which shall be very efficient in action.

The ordinary piston ring now in common use consists of a split ring of spring steel or other metal, of larger diameter than the internal diameter of the cylinder, and necessarily it must be compressed when it is inserted in the cylinder of the engine; consequently, when released, it presses against the inner face of the cylinder, creates friction, and at the same time causes considerable wear upon the internal face of the cylinder.

One of the objects of this invention is to provide a piston ring which shall completely obviate all of such objectionable features, and still provide a practically perfect joint between the piston and cylinder.

To such ends this invention consists in the several novel features of construction hereinafter fully set forth and claimed.

35 The invention is clearly illustrated in the drawing furnished herewith, of which:

Figure 1 is a side elevation of a fragment of a piston, showing a number of my improved piston rings applied thereto, Fig. 40 2 is a central, vertical section taken on line 2-2', Fig. 1, Fig. 3 is a horizontal section taken on the line 3-3', Fig. 2, Fig. 4 is a face view of a blank, from which one of the piston rings is constructed, and showing 45 the same as having been rolled into the proper cross section, prior to the final action of giving it its ring like form, Fig. 5 is a detail, vertical section of a fragment of the piston and one ring, Fig. 6 is a perspective view of one of the rings, Fig. 7 is a side elevation of a fragment of a cylinder

showing a slightly modified form of ring retaining means and Fig. 8 is a detail, vertical section taken on the line 8-8, Fig. 7.

Referring to said drawing, 10, designates 55 a piston of which 11, designates its cylindrical wall, and 12, the head thereof. In accordance with the common practice, circumferential grooves 13, are formed on the outer face of the cylindrical wall 11, of the 60 piston, for the reception of the piston rings, and in the preferred form of the invention said grooves 13, are shown as having a rectangular cross section. In each of said grooves 13, is seated a piston ring, 14, constructed in accordance with the present invention. Each ring comprises a strip of comparatively thin metal, originally wider than the groove 13, and rolled by any suitable means to present the cross section best 70 seen in Fig. 5. The reference numeral 16, designates the cylindrical portion of the ring, which is designed to bear against the inner face of the cylinder, and the edges of said strip beyond said cylindrical portion 75 16, are each rolled down to form reverse curves 17 and 18. The distance between the marginal edges of the curved portions 18, is approximately equal to the distance between the edges 19, of the grooves 13, although if 80 desired said grooves may be a trifle wider than the width of the finished ring. The ends 20, of the ring 14, are cut away on an angle, here shown, as of approximately forty-five degrees, and the length of the 85 strip from which the ring is formed is such that when bent or curved upon itself the edges of the ring will fit and seat upon the base of the groove in the piston with the terminal ends 20, contacting with each other. 90 To form a more perfect fit a light cut may be taken off the rings after they have been inserted in the groove, thus insuring a perfectly cylindrical bearing surface.

It is to be observed that by reason of the 95 fact that the strip is bent to fit the base of the groove, or perhaps bent to a slightly smaller diameter so as to press against the base of the groove, there is no tendency for the ring to bear, with any unnecessarily 100 great pressure, against the inner face of the cylinder and cause any great amount of

friction; furthermore the pressure of the rings against the cylinder is due to the cross section of the ring, which is constant at all points throughout. If the external diameter of the ring is made a shade larger than the internal diameter of the cylinder, the result will be a tendency to slightly compress the ring against the base of the groove and this is permitted by reason of the reversed curved edges of the ring. The rings may be made of very light gage metal and preferably a high carbon steel is employed containing a very small percentage of manganese, although of course, any suitable metal may be employed in the construction of the rings.

In the modified form shown in the Figs. 7 and 8, the groove 13^a, is shown as formed with overhanging edges 13^b, that engage with the outer sides of the reversed curved edges 18^a, of the ring 14^a. With the use of the overhanging edges 13^b it may be found unnecessary to curve or bend the ring before inserting it in the groove, although a more perfect and accurate external face may be given the ring by curving into form before inserting into the groove. The overhanging edges 13^b, are shown as formed with oppositely disposed notches 13^c, through which the ring may be inserted in the groove 13^a.

I am aware that various alterations and modifications of the exact form of the ring are possible without departing from the invention and I do not, therefore, desire to limit myself to the exact form shown and described, except as may be necessitated by the prior state of the art.

I claim as new and desire to secure by Letters Patent:

1. A piston ring, uniform in cross section throughout, and comprising a cylindrical portion adapted to bear against the internal wall of a cylinder and having its edge portions bent inward from the cylindrical portion at a wide angle with respect to each other, to form resilient portions adapted to bear against the base of an annular groove in a piston.
2. A piston ring, comprising an annular strip of metal of uniform cross section, and consisting of a cylindrical portion adapted to bear against the internal wall of a cylinder and having its edge portions bent inward and then laterally away from each other in the form of reverse curves to form resilient portions adapted to bear against the base of an annular groove in a piston.
3. A piston ring, comprising an annular strip of metal having overlapping ends and of uniform cross section throughout, said strip consisting of a middle cylindrical portion adapted to bear against the internal wall of a cylinder and having its edge por-

tions bent inward from the cylindrical portion in widely diverging directions, with respect to each other to form resilient portions adapted to bear against the base of an annular groove in a piston.

4. A piston ring, uniform in cross section throughout, and comprising a strip of metal bent into ring-like formation, consisting of a middle cylindrical portion adapted to bear against the internal face of a cylinder and having its opposite edge portions curved inward from the cylindrical portion and then away from each other to form resilient portions of less diameter than the outer diameter of the cylindrical portion and adapted to bear against the base of an annular groove in a piston.

5. A piston ring, comprising an annular strip of metal of uniform cross section throughout, the cross section being substantially of dish-like formation having a flat base and outwardly flaring portions.

6. A piston ring, comprising an annular strip of metal having a middle cylindrical portion adapted to bear against the internal wall of a cylinder and resilient portions formed at the edges of the cylindrical portion and diverging from each other at a wide angle and adapted to bear against the base of an annular groove in a piston.

7. A piston ring, of uniform cross section throughout, and comprising a cylindrical portion adapted to bear against the internal wall of a cylinder and having its opposite edge portions bent inward in the form of reverse curves; the two edge portions diverging from each other and being arranged to bear against and seat upon the base of an annular groove in a piston.

8. A piston ring, comprising a strip of metal uniform in cross section throughout, and having a cylindrical portion adapted to bear against the internal wall of a cylinder, its opposite edge portions being bent inward at a wide angle from the cylindrical portion to form annular resilient portions that seat upon the base of a groove of a piston.

9. A piston ring, comprising an annular strip of metal uniform in cross section throughout and having its ends overlapping each other, the middle portion of said annular strip being of cylindrical form and its edge portions having reverse curve bends, extending toward the axis of the ring, to form resilient portions adapted to bear against the base of an annular groove of a piston.

10. A piston ring, comprising a strip of spring metal uniform in cross section throughout and bent into annular form with its ends overlapping each other, the middle portion of said annular portion of said annular strip being cylindrical in form and adapted to bear against the internal wall of a cylinder, and the opposite edge portions

being bent into reverse curves extending generally toward the axis of the cylindrical portion and forming resilient portions for the cylindrical portion, said edge portions being adapted to seat upon the base of an annular groove of a piston.

In witness whereof I have hereunto ex-

cuted the above at Chicago, county of Cook, this 30th day of June A. D. 1913.

GEORGE R. RICH.
